BEER BOTTLE

Martin L. Schmidt, 1913 Meadow Road,
Walnut Creek, Calif.

Filed Dec. 4, 1963, Ser. No. 77,654

Term of patent 14 years

(Cl. D58—9)

The characteristic feature of my design resides in the combination on the footed bottle disclosed of the slip-over, domed cap portion, suggesting the head on draft beer.

I claim:

The ornamental design for a beer bottle, as shown and described.
